Inventor:
Thomas S. Evans:
By Thos. H. Bro. atty's.

UNITED STATES PATENT OFFICE.

THOMAS S. EVANS, OF ST. LOUIS, MISSOURI, ASSIGNOR TO THE JACKES-EVANS MANUFACTURING COMPANY, OF SAME PLACE.

DESIGN FOR A STOVE.

SPECIFICATION forming part of Design No. 31,558, dated September 26, 1899.

Application filed August 5, 1899. Serial No. 726,338. Term of patent 7 years.

To all whom it may concern:

Be it known that I, THOMAS S. EVANS, a citizen of the United States, residing at St. Louis, in the State of Missouri, have invented and produced a new and original Design for a Stove, of which the following is a specification, reference being had to the accompanying drawing, forming part thereof.

The drawing is a perspective view of a stove, showing my new design.

The leading or characteristic feature of my design consists of an ornamentation for a stove, having Grecian rectilinear fret arranged or disposed over the surfaces of the ornamentation.

1 designates the stove-body surmounting a base 2.

3 is a rim bearing Grecian rectilinear fret 4. 5 is a protuberance bearing Grecian rectilinear fret 6. On the stove-body surrounding 20 the protuberance is Grecian rectilinear fret 7. 8 are rail-like foot-rests bearing Grecian rectilinear fret 9.

10 is a rim at the upper end of the stove-body, bearing Grecian rectilinear fret 11. 25

Having thus described my invention, the following is what I claim as new therein and desire to secure by Letters Patent:

The design for a stove substantially as shown and described.

THO. S. EVANS.

In presence of—
E. S. KNIGHT,
M. P. SMITH.
